UNITED STATES PATENT OFFICE.

JAMES V. FORT, OF PHILADELPHIA, PENNSYLVANIA.

SHUTTER BOWER AND FASTENER.

SPECIFICATION forming part of Letters Patent No. 287,816, dated November 6, 1883.

Application filed September 11, 1883. (No model.)

To all whom it may concern:

Be it known that I, JAMES V. FORT, a citizen of the United States, and a resident of the city and county of Philadelphia, and State 5 of Pennsylvania, have invented a new and useful Improvement in Devices for Securing Window-Shutters, of which the following is a specification.

The object of my invention is to furnish a 10 device for securing window-shutters which cannot be opened from the outside of the window, and which will form a perfect device for bowing the shutters and securing them when shut.

15 In the accompanying drawings, forming part of this specification, and in which similar letters of reference indicate like parts throughout the several views, Figure 1 represents a window-shutter with my invention 20 used as a bolt; Fig. 2, the invention when used to bow the shutters; Figs. 3, 4, and 5, views of different styles of the invention; Figs. 6, 7, 8, 9, 10, 11, 12, and 13, top and side views of the pins for securing my invention; 25 and Fig. 14, a top view of my invention when opened to bow the shutters.

A B are two pieces of metal secured together by a pivot or other suitable means. C is a slot through which the shank *a* of the pin 30 I passes. D D are teeth upon the upper side of this slot, which grasp the shank *a* of the pin I. E is a hole through which the head of the pin I can pass when it is desired to remove the invention from the shutter. F is a 35 square or rectangular recess opening into E, which may grasp the shank *a* of the pin I and act as a wrench in screwing said pin I up. G and H represent the window-shutters, while K represents the plate on the bottom of I.

40 The pins I may be of several forms, and are attached to the shutters at suitable distances from the edges, as shown in Figs. 1 and 2. The pins shown in Figs. 6, 7, 8, and 9 consist of a rectangular shank, *a*, having a head, *b*, and base-plate K, and are secured to the shutters by screws. These screws should be so arranged that when the fastening A B is in place 45 their heads will be covered by said fastening, so as to prevent their removal while said fast-

ening is in place. The pins shown in Figs. 50 10, 11, 12, and 13 consist of a head, *b*, shank *a*, plate K, (which may be part of the pin, or separate from it,) and screw N. These pins are simply screwed into the shutter.

In attaching my invention to the shutters, 55 if the heads of the pins are both small enough to pass through the opening E, the pins are first and permanently secured to the shutters, the head of one is passed through the opening E, and the fastening over until the other pin 60 can be passed through E and its shank *a* is in the slot C. If one head is too large to pass through E, this pin is first put through the slot C and the pin is screwed into the shutter. The rectangular slot F may be used as a wrench 65 to screw the pins up. If it is desired to use the fastening as a bolt to hold the shutters securely together, the pins are grasped by the teeth of one part of the fastening, as A, Fig. 1. If it is desired to bow the shutters, the 70 fastening is placed as shown in Fig. 2—that is, one pin is grasped by the teeth of A and the other by those of B. The amount of opening that can be given to the shutters depends upon the length of A and B, and this opening 75 can be regulated at will by placing the pins between different teeth.

The fastening shown in Fig. 4 represents one constructed of wire.

Having thus described my invention, I claim 80 and desire to secure by Letters Patent—

1. The herein-described device for bowing and fastening window-shutters, consisting of the metal pieces A B, pivoted or otherwise suitably secured together, and furnished with 85 a slot, C, teeth D, and opening E, in combination with the pins I, the whole arranged and operating substantially as set forth.

2. The herein-described device for bowing and fastening window-shutters, consisting 90 of the metal pieces A B, suitably secured together, and having a slot, C, teeth D, opening E, and opening F, and the pins I, all substantially as and for the purposes set forth.

JAMES V. FORT.
